CLAIM

The ornamental design for an industrial robot, as shown and described.

DESCRIPTION

FIG. 1 is a front-left perspective view of an industrial robot showing a first embodiment of our new design;

FIG. 2 is a left view thereof;

FIG. 3 is a right view thereof;

FIG. 4 is a rear view thereof;

FIG. 5 is a front view thereof;

FIG. 6 is a top view thereof; and

FIG. 7 is an exploded view thereof;

FIG. 8 is a front-left perspective view of an industrial robot showing a second embodiment of our new design;

FIG. 9 is a left view thereof;

FIG. 10 is a right view thereof;

FIG. 11 is a rear view thereof;

FIG. 12 is a front view thereof;

FIG. 13 is a top view thereof; and

FIG. 14 is an exploded view thereof;

FIG. 15 is a front-left perspective view of an industrial robot showing a third embodiment of our new design;

FIG. 16 is a left view thereof;

FIG. 17 is a right view thereof;

FIG. 18 is a rear view thereof;

FIG. 19 is a front view thereof; and

FIG. 20 is a top view thereof;

FIG. 21 is a front-left perspective view of an industrial robot showing a fourth embodiment of our new design;

FIG. 22 is a left view thereof;

FIG. 23 is a right view thereof;

FIG. 24 is a rear view thereof;

FIG. 25 is a front view thereof; and

FIG. 26 is a top view thereof;

FIG. 27 is a front-left perspective view of an industrial robot showing a fifth embodiment of our new design;

FIG. 28 is a left view thereof;

FIG. 29 is a right view thereof;

FIG. 30 is a rear view thereof;

FIG. 31 is a front view thereof; and,

FIG. 32 is a top view thereof.

(Continued)

The color of the industrial robot of the third, fourth, and fifth embodiments form a part of the claimed design. The background in the third, fourth, and fifth embodiments form no part of the claimed design.
